FOUNDRY EQUIPMENT

George D. Johnson, Pendleton, Ind., assignor to
 General Motors Corporation, Detroit, Mich., a
 corporation of Delaware

Application October 26, 1951, Serial No. 253,237

2 Claims. (Cl. 214—18)

1

This invention relates to foundry equipment and is particularly concerned with a cupola charging bucket and means for operating said bucket.

The basis of the invention is, therefore, to provide an improved charging bucket and means for operating said bucket wherein the usual wishbone is eliminated in the cupola and wherein the bucket is operated entirely through the hoist whereby better operational control is obtained.

In accomplishing these ends, a bridge is provided connecting the cupola with a point remote therefrom upon which the bucket may move laterally with respect to the cupola, means being provided at the hoist end of the bridge for automatically disconnecting the bucket from the bridge so that the bucket may be lowered to the charging floor.

Further improvements and advancements in the art will be apparent reference being had to the accompanying drawings, wherein a preferred embodiment of the present invention is clearly shown.

In the drawings:

Fig. 1 shows a side view of a charging bucket and support frame therefor, wherein the bucket is in released position with respect to the frame.

Fig. 2 is a side view of the bucket and frame shown in Fig. 1, taken in the direction of the arrow marked 2.

Fig. 3 is a view taken in the direction of arrow marked 3 in Fig. 2.

Fig. 4 is a view similar to Fig. 1 with the bucket in supported position with respect to the frame.

Fig. 5 is a view taken in the direction of the arrow marked 5 in Fig. 4.

In foundry operations, the cupola is charged by means of a bucket, which carries charges of pigiron, coke, limestone and any other materials which are desired to be placed in the cupola. These charges are periodically added to the cupola through the charging door at the top thereof by means of the bucket which has a bottom therein that opens to permit emptying of the contents. This bucket must necessarily be recharged on the charging floor which is remote from the cupola and then being hoisted to a position parallel to the charging door of the cupola and finally run laterally toward the cupola until the bucket is actually inside the cupola. These operations are carried out by a crane hoist which lifts the charge bucket from the floor and then carries the bucket along a bridge that is positioned so that the bucket may enter the charging door of the cupola. Normally, the bucket is placed

2

in the cupola and is lowered until contact is made with the wishbone within the cupola which automatically opens the bottom of the bucket and permits the materials therein to be emptied. This wishbone, being positioned inside the cupola, is frequently damaged, thereby requiring replacement or repair and for this reason its usefulness in connection with the charging bucket is often impaired.

10 I have devised an entirely new assembly as embodied in an apparatus for carrying a charging bucket into and out of the cupola and for automatically gripping the charging bucket or releasing the same in accordance with its particular 15 position wherein the bucket is released when retracted to a position above the charging floor but is held in a frame in all other positions of operations.

Referring specifically to the drawings, a frame 20 is shown which carries a charging bucket 22 through a hoist hook 24 that, in turn, is supported on cables 26 that run over pulley wheels 28. The cables 26 are connected to a reel within the crane (not shown) and are operable by the crane operator so that bucket 22 may be suitably controlled.

The frame 20 is suitably supported upon rollers which move along the bridge track (not shown). The frame 20 includes a pair of pivotally mounted arms 32 and 34 extending downwardly therefrom and controlled by a pair of angularly disposed rods 36 and 38 which are pivotally joined at 40. The rods 36 and 38 are pivotally attached to the arms 32 and 34 respectively. It will be apparent that, when the pivot point 40 is free, the weight of the arms 32 and 34 will cause the same to move inwardly so that they hang substantially vertical with respect to the frame 20. However, when the pivot point 40 abuts an immovable part, such as a portion of the hoist housing 42 as the bucket is drawn rearwardly against the housing, the pivot point 40 is moved toward the right as noted in Fig. 3, thereby causing the rods 36 and 38 to be pushed outwardly to pivot the arms 32 and 34 outwardly.

45 The bucket 22 includes an annular rim 44 therearound having a pair of opposed ears 46 attached thereto. The arms 32 and 34 are, in effect, inverted U-shaped structures as shown in Fig. 2 and the lower legs thereof are connected 50 by cross bars 48 which are contoured as noted in Fig. 3 to fit the rounded shape of the bucket 22. Thus, when the arms 32 and 34 hang down, the bucket rim 44 rests upon the cross bars 48 and is held firmly thereon through the interlock of 55 the ears 46. However, when the bucket is in re-

tracted position and away from the cupola so that the pivot point 40 abuts the hoist housing 42, the arms 32 and 34 are pushed outwardly to release the bucket from the ears 46. In this instance, it may be necessary for the crane operator to lift the bucket slightly through the medium of the cables 26.

It will be noted that when the arms 32 and 34 are in holding position, the bucket 22 cannot be lowered so that when the operator causes cables 26 to elongate, the hook 24 moves downwardly due to the weight of a pull-bar 50 and an attached bell bottom 51 of the bucket. In this manner, the bottom 51 of the bucket drops downwardly as shown in Fig. 4 to permit emptying of the contents thereof. In this position, the bucket will be within the cupola. When the contents of the bucket has been emptied, the hoist is reversed and cables retract the hook 24, bar 50 and bottom 51 until the bottom 51 lifts the entire bucket 22 upwardly so that the ears 46 are out of engagement with the bar 48. The entire bucket assembly is then retracted on the bridge until pivot point 40 hits the hoist housing 42, causing the arms 32 and 34 to pivot outwardly whereupon the hoist operator may lower the entire bucket by means of cables 26 to the charging floor.

Thus it will be noted that the charging bucket is supported entirely by the crane hoist. No wishbone is present in the cupola and the bucket is independent of the cupola at all times and always under complete control of the hoist operator. The holding device as embodied in the arms 32 and 34 and pivot rods 36 and 38 is not subjected to excessive heat, since this holding device is never in the cupola except during the period when the bucket is being emptied, thereby elongating the period of usefulness of the holding device and maintaining the same in satisfactory operating condition. Furthermore, it is quite apparent that since the bucket is carried entirely by the crane, the bucket is under complete control of the operator at all times as differentiated from the old type wishbone unloader wherein the bucket often became jammed within the cupola due to the build-up of contents thereof against the walls of the cupola and inability of the operator to lift the bucket with respect to the cupola without causing the bottom thereof to close since the entire bucket was supported by the bottom. In the present instance, it is possible to move the bottom up and down while the bucket is suspended in the cupola to cause dislodgment of any jammed material in the bucket, thereby greatly facilitating the unloading operation.

While the embodiment of the present invention as herein disclosed, constitutes a preferred form, it is to be understood that other forms might be adopted.

What is claimed is as follows:

1. A charging bucket assembly for use in the charging of cupolas and the like, wherein the bucket is movable to two extreme positions upon an elongated supporting bridge one of which positions is aligned with and proximate the charging door of a cupola and the other position is remote from said charging door wherein the bucket is vertically movable to the bridge; the combination comprising, a charging bucket having an annular

rim carried thereon, a pair of opposed spaced ears associated with said rim, a bottom for said bucket relatively vertically movable thereto and capable of being lowered relative to said bucket for permitting discharge of the contents thereof, a support frame horizontally movable on said bridge for carrying said bucket, gripping means pivotally carried by said frame for engaging said ears for normally maintaining said gripping means on said rim, said gripping means including a pair of bifurcated arms pivotally mounted on said frame and movable laterally to said frame by gravity toward each other into said gripping position, and a release means for said gripping means consisting of a pair of pivotally mounted levers for overcoming gravity and for causing said pair of arms to be moved away from one another, said release means associated with the frame and operable only when the frame and bucket are in the position remote from the charging door of said cupola for releasing said gripping means whereby the bucket may be lowered vertically with respect to the frame.

2. A charging bucket assembly for use in connection with foundry cupolas and the like comprising in combination; a support frame carried by a bridge and horizontally movable thereon, a bucket bottom movably carried by said frame, a side wall for said bucket capable of being carried by said bottom, a continuous annular outstanding flange on the exterior of the side wall of said bucket, clamping means pivotally associated with said frame for normally holding the bucket side whereby the bottom may be moved relative thereto, said clamping means including a pair of spaced substantially U-shaped elements having a central portion and extending arm portions, each of said U-shaped elements being horizontally pivotally mounted on and carried by said frame and parallel to said frame at the central portions thereof whereby respective arm portions of said U-shaped elements may be moved toward each other by the force of gravity into engagement with said bucket on opposite sides thereof, gripping means carried by ends of extending arm portions of said U-shaped elements, said gripping means having a portion thereof conforming to the radius of curvature of the external surface of the bucket and adapted for engaging portions of said flange on the bucket whereby said bucket is maintained in position relative to said frame when said U-shaped elements pivotally move to position by gravity, and release means for disengaging the clamping means whereby the bucket and bottom may be moved as a unit relative to said frame, said means including a pair of pivotally mounted levers associated with said frame and having actuating means attached to said levers and operable for spreading said U-shaped elements for releasing said bucket when said frame is in one position only on said bridge.
